US0D1050023S

(12) **United States Design Patent** (10) **Patent No.:** **US D1,050,023 S**
Peng (45) **Date of Patent:** **** Nov. 5, 2024**

(54) **CHARGING STATION FOR ELECTRIC VEHICLES**

(71) Applicant: **Autel Digital Power Co., Ltd.**, Shenzhen (CN)

(72) Inventor: **Anliang Peng**, Shenzhen (CN)

(73) Assignee: **Autel Digital Power Co., Ltd.**, Shenzhen (CN)

(**) Term: **15 Years**

(21) Appl. No.: **29/874,093**

(22) Filed: **Apr. 14, 2023**

(30) **Foreign Application Priority Data**

Oct. 20, 2022 (CN) 202230693304.6

(51) **LOC (14) Cl.** **13-02**

(52) **U.S. Cl.**

USPC **D13/107**

(57) **CLAIM**

The ornamental design for a charging station for electric vehicles as shown and described.

DESCRIPTION

FIG. 1 is a front, right and top perspective view of a charging station for electric vehicles showing my new design;

FIG. 2 is a rear, left and bottom perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof;

FIG. 8 is a bottom plan view thereof;

FIG. 9 is an enlarged view of an encircled portion 9 of FIG. 1; and,

FIG. 10 is an enlarged view of an encircled portion 10 of FIG. 1.

The broken lines depict portions of the charging station for electric vehicles that form no part of the claimed design.

1 Claim, 10 Drawing Sheets
